STOP MOTION FOR TEXTILE MACHINES

William J. McKinney, Stonington, Conn., assignor
to The Atwood Machine Company, Stonington,
Conn., a corporation of Connecticut

Application July 2, 1940, Serial No. 343,598

3 Claims. (Cl. 57—80)

This invention relates to textile machines, and particularly to doubling and twisting machines for rayon, silk and other fibres. More particularly the invention relates to a stop motion for promptly stop operation of individual units of the machine when a strand breaks before or after reaching the feeding mechanism, or when broken strands become wrapped around the feeding mechanism.

An object of the present invention is to provide an improved stop motion particularly adapted for a doubling and twisting machine for textile fibres that may be mounted upon the housing for the feeding mechanism and which will be simple in construction and which will act promptly to stop the twisting operation if one or more strands break or become wrapped around the feeding mechanism, which generally is in the form of a wheel or a pair of wheels.

Another object of the invention is to mount a stop motion lever, having yarn guiding eyes thereon, pivotally upon an arm which may swing about the axis of rotation of the feed mechanism, and which is normally retained in its normal or operative position by means of a light spring.

In doubling and twisting machines for textile fibres, it is usual and standard practice to provide individual drop wires each held in place by one of the strands being twisted. In the event one of the strands breaks its drop wire falls and a weighted portion of the drop wire is interposed in the path of motion of an oscillating or rotating member. A latch is released by this oscillating or rotating member which disengages the feed mechanism and thus stops the twisting operation at that unit. In addition to the possibility of a single strand breaking before it reaches the feed mechanism, the combined strand between the feeding mechanism and the twisting unit may break. To stop the feeding mechanism when this strand breaks additional stop mechanism is sometimes provided. Also when the strands become entangled or wrapped about the rotating members of the feeding mechanism, a stop motion should act to promptly stop rotation of the feeding mechanism so that the wrapped strands may be removed and twisting again started.

In the present embodiment of the invention the stop motion actuating members are mounted on the housing for the feeding mechanism which in the drawing is in the form of a "Cleveland" feed wheel. In the event an individual strand or the combined twisted strand breaks, or if the strands become wrapped about the feed wheels

at any twisting unit, that unit is promptly rendered inoperative.

With the above and other objects in view the invention includes the features of construction and operation set forth in the following specification and illustrated in the accompanying drawing.

In the accompanying drawing annexed hereto and forming a part of this specification, I have shown the invention embodied in a standard form of doubling and twisting machine but it will be understood that the invention can be otherwise embodied and that the drawing is not to be construed as defining or limiting the scope of the invention, the claims appended to this specification being relied upon for that purpose.

In the drawing:

Fig. 1 is a side elevation of the feeding mechanism for a doubling and twisting machine, the stop mechanism forming the present invention being shown therewith.

Fig. 2 is a front elevation partly in section and showing the feed wheels and stop motion actuator associated therewith; and

Fig. 3 is a detail sectional view taken on the planes of broken line 3—3 in Fig. 1.

In the above mentioned drawing, there has been shown but one embodiment of the invention which is now deemed preferable but it is to be understood that changes and modifications may be made within the scope of the appended claims, without departing from the spirit of the invention.

Briefly, and in its preferred aspect, the invention may include the following principal parts: first, a feeding mechanism housing supported for movement to operative and inoperative positions and provided with yarn feeding mechanism in the form of suitable rotatably mounted wheels; second, a radial arm mounted co-axially with said housing and wheels for limited swinging movement relative thereto; third, a lever having thread guides thereon mounted for tilting movement on the outer end of said arm; and fourth, a reach arm attached at one end to said lever and extending to the drop wire operated latch mechanism to disengage the feeding mechanism from its driving means and stop operation at that unit.

Referring more in detail to the figures of the drawing there is shown at 10 a housing within which are mounted feed wheels 11 rotatably mounted on a central stud 12. The stud 12 is mounted for rotation within the housing 10 and is retained against removal therefrom by means of a washer and wire ring. To rotate the feed

wheels 11 one of them is attached directly to a gear 14. The second feed wheel intermeshes with the first wheel upon an axis slightly oblique and eccentric thereto, so that both wheels are forced to rotate simultaneously and their peripheries have a slight axial and eccentric movement. As the particular form of feed wheels 11 over which the strands are wrapped and their operation form no part of the present invention, further description is not thought to be necessary. It will be sufficient to state that the form of feed wheel is well known and maintains each successive wrap of yarn around their peripheries suitably spaced from the others.

The housing 10 as shown in Fig. 1 is pivotally supported upon a shaft 15 mounted in a bracket 16 forming a fixed part of the twisting machine. It will be understood that a bracket 16 is provided for each housing 10 and there is a housing 10 for each twisting unit of the machine. Extending rearward from the housing 10 is an arm 17 preferably formed integrally with the housing 10 and having its end bifurcated as shown. Engaging this end of the arm 17 is a short stud 18 secured on a vertically movable rod 19. Movement of the rod 19 downward from the position shown in Fig. 1 serves to raise the housing slightly and disengage the gear 14 from its driving gear 20. These driving gears 20 for each unit are preferably provided at spaced positions on shaft 21 which may extend the full length of the machine and may be driven in any desired manner by means not shown. As before described, mounted on the central stud 12 is an arm 22 the outer end of which fits within an recess 23 sufficiently wide to permit a limited swinging movement of the arm 22. This arm 22 as shown may be fastened to stud 12 as by means of a small screw so that the stud 12 must also oscillate with the arm 22. At the outer end of the arm 22 is a tilting lever 24 weighted at its rear end and having thread guiding members 25 and 26 adjustably fitted thereon as shown. To retain the arm 22 in the position shown in Fig. 1 is a slight spring 27, one end of which is fastened to an intermediate portion of the arm and the opposite end to a projection formed in the housing 10. Extending obliquely upward from the tilting lever 24 is a reach rod 28, the lower end of which is pivotally attached to the rear of lever 24 and its upper end is supported over the drop wire support 29. The upper end of this rod 28 has an extension 30 directly over the latch releasing lever 31 so that slight downward movement of the rod 28 oscillates lever 31 and interposes its rear end in the path of the stop motion actuator 32. When oscillated to its tripping position a projection on actuator 32 forces the lever 31 forward and releases an abutment on the lever from below a lateral protection 33 on rod 19 so that rod 19 may move downward and raise the housing 10 and its gear 14 so that this gear is disengaged from gear 20. The actuator 32, the latch lever 31 and the drop wires 34 and their operation may be similar to means now employed and form no part of the present invention.

In operation, if one of the strands 35 above the housing should break, its drop wire 34 would fall backward so that the weighted heel 36 of the drop wire would oscillate lever 31. In the usual manner of action, the drop wire 34 would fall between the strands 35 and the housing 10 so that the heel 36 would strike the projection 32 and force the lever 31 forward so that the gear 14 would be disengaged from the gear 20.

manner. Should the combined twisted strand 35 below the housing 10 break, the lever 24 would tilt in a direction to move its weighted rear end down and pull rod 28 down so that the projection 30 at its upper end would similarly oscillate lever 31.

In addition, the stop motion should act promptly, when the strands become wrapped around the wheels 11 and interfere with the proper feeding of the strands. This may occur while the strand 35 below the feeding mechanism continues to exert sufficient tension to prevent tilting of the lever 24. To actuate the stop motion when this occurs dependence is placed upon forward movement of the radial arm 22 which pulls the reach rod 28 forward and downward so that its upper end extension 30 oscillates the trip lever 31. The effect upon the wheels 11 when strands become wrapped around them is to effectively bind them together and restrict their relative axial and eccentric movements. The wheels therefore tend to rotate together as one member which requires rotation with them of the central shaft 12. This movement of the central shaft 12, however, forces the arm 22 to move with it for the reason that this arm is fastened directly to the shaft. As soon as the arm 22 has moved slightly forward the arm 28 has been pulled sufficiently to actuate the latch or trip lever 31 and stop rotation of the feed wheels 11 by disengaging their gear 14 from driving gear 20.

2. A stop motion for textile machines comprising in combination, a feed mechanism housing movable to operative and inoperative positions, a substantially radial arm mounted for limited swinging movement thereon, a lever having thread guiding members thereon pivotally mounted at the outer end of said arm, and a stop motion actuating rod attached to said lever, whereby oscillation of said lever moves said rod to a position to actuate said stop motion and move said housing to its inoperative position.

3. A stop motion for textile machines comprising in combination, a feed mechanism housing movable to operative and inoperative positions, a substantially radial arm mounted for limited swinging movement thereon, a lever having thread guiding members thereon pivotally mounted at an intermediate point to the outer end of said arm, and a stop motion actuating rod attached to said lever at one end thereof whereby swinging movement of said arm and lever moves said rod to a position to actuate said stop motion and move said housing to its inoperative position.

4. A stop motion for textile machines comprising in combination, a feed mechanism housing movable to operative and inoperative positions, a substantially radial arm mounted for limited swinging movement thereon, a lever weighted at one end and having thread guiding members thereon pivotally mounted at the outer end of said arm, and a stop motion actuating rod attached to the weighted end of said lever, whereby oscillation of said lever moves said rod to a position to actuate said stop motion and move said housing to its inoperative position.

5. A stop motion for textile machines comprising in combination, a feed mechanism housing movable to operative and inoperative positions, a substantially radial arm mounted for limited swinging movement thereon, a lever weighted at one end and having thread guiding members thereon pivotally mounted at the outer end of said arm, and a stop motion actuating rod attached to the weighted end of said lever, whereby oscillation of said lever moves said rod to a position to actuate said stop motion and move said housing to its inoperative position.
